SUPPORT OR BRACKET OF HANGER TYPE

Raymond E. Beegle, East St. Louis, Ill.

Application August 30, 1939, Serial No. 292,586

10 Claims. (Cl. 248—235)

This invention relates to improvements in supports or brackets of hanger type, for supporting wall shelves and the like, as well as a shelving assembly utilizing an improved form of suspension bracket.

An object of the invention is to provide an improved bracket adapted as a tension or hanger element, for engaging and supporting the outer or overhanging edge of a wall shelf, and adapted further, for supporting the inner or wall-abutting edge of a wall shelf thereabove. Thus the bracket serves to support in part, adjacent upper and lower shelves. Moreover, in effecting the support of an outer edge of one shelf and the inner edge of another, the bracket thereby determines the vertical spacing of the shelves; thus in a series or bank of such shelves, uniform vertical spacing thereof may be attained through the utilization of equal length brackets of the improved type indicated, and conversely, by employing brackets of one length between certain of the shelves, and brackets of another length between others thereof, any desired relative spacing of the shelves may be readily attained.

Additional objectives of the invention include the provision of a tension-type shelf hanger of such improved design that the weight of the shelving, with or without superposed loading, tends to draw the shelving to the wall or other vertical support for the shelf assembly.

Yet another object of the invention is attained in an improved tension bracket or shelf hanger which bridges opposite margins of superposed shelves, and yet is of such design that a given size of bracket or hanger is of a wide range of adaptability, enabling it to be utilized with shelving of widths differing over a range of several inches.

A still further object of the invention is attained in an improved readily detachable combination of shelving or shelf hangers, such that the shelving is easily removable from and engageable with the hangers or brackets at any time, and, expressed as a preference in relation to the disclosed example, the shelving is endwise insertable and removable in and from the hanger or bracket assembly.

An additional and important object of the invention is attained in a shelf hanger of such design that the hanger or bracket elements impose the greater proportion of load on their holding members, such as wall screws for example, in shear, and only to a minor extent in a direction axially of the holding members, it being noted that in many older designs there is a marked

tendency of increased loading of the shelves to impose an axial pull and so to withdraw the screws or the like from the wall or other vertical support.

Another object resides in the provision of an improved shelf bracket of hanger type, in which the ends thereof are substantially identical in structure and form, but relatively reversed, whereby to adapt either end for supporting engagement with the overhanging edge of a lower shelf, or the inner edge of an upper shelf, a given end of the bracket functioning in the first mentioned respect when the bracket is disposed in an operative position, and functioning in the second mentioned respect only upon reversing the bracket, end for end, and re-locating it in the same operative position.

Another object is to provide a bracket of the form and for the purpose indicated, in which each of its ends is adapted for bracket-mounting upon a wall or other vertical supporting element, each end being provided for this purpose, with an aperture or slot to accommodate a supporting element of suitable form, the bracket-mounting cooperation of the supporting element and the aperture being such as to facilitate easy and rapid attachment or detachment of the bracket relative to the supporting element, and yet such as to preclude any casual or unintended disconnection of the hanger or bracket from its support.

Yet another object resides in the provision of improved shelf-supporting bracket elements of the type indicated, which may be readily manufactured at low unit cost, and which are well adapted for compact grouping or nesting, to facilitate storage, packing and shipping thereof.

Further objects and advantages will readily appear from the following description of a preferred embodiment of the invention, as illustrated by the accompanying drawing, in which:

Fig. 1 is a vertical, end elevation of a bank of wall-shelves, employing as supports therefor, brackets of the type forming the subject of the present invention; Fig. 2 is a front elevation of the shelf-bank of Fig. 1; Fig. 3 is an enlarged elevation in perspective, of a preferred form of the improved bracket; Fig. 4 is a fragmentary sectional elevation, greatly enlarged, of the shelf and bracket assembly, showing the manner of mounting the bracket; Fig. 5 is a vertical, transverse section of a shelf and bracket assembly, illustrating a modification in the support of a shelf by the brackets; Fig. 6 is a fragmentary section thereof, as viewed from line 6—6 in Fig. 5, and Fig. 7 illustrates the manner of grouping or

nesting the brackets, for storage or shipment purposes.

Referring to the drawing in detail, as by suitable characters of reference, there is illustrated in Figs. 1 and 2 a group or bank of wall shelves arranged in vertically spaced relation on a wall or other vertical support 10. In the present example, three shelf members 11, 12 and 13 comprise the shelf-bank, each being supported upon the wall 10 by improved bracket elements 14 of tension or hanger type, forming of themselves, and in combination with the shelving, the subject of the invention.

The brackets, one of which is clearly shown in detail in Fig. 3, may be formed from one-piece, flat strip or bar stock of suitable gauge or thickness, the structural shaping of the bar and its ends being accomplished in any suitable, well-known manner, as by stamping and pressing operations. As appears from the drawing, particular reference being had to Fig. 3 therein, the bracket 14 is comprised of a linear body portion 15 of flat-bar or strip form, having its ends 16 and 17 formed to provide hook-like elements which project oppositely and outwardly from the plane of the flat portion of the body. The end 16 which presents a substantially V-shaped bend, in the nature of a right angled terminal, includes an intermediate portion 18 projecting laterally and forwardly of the body 15, at an obtuse angle thereto, and an end portion 19 directed rearwardly of the end 16 and substantially normal to the portion 18. A rectangular aperture or slot 20 is provided in the portion 18 to accommodate a bracket supporting element, such as the rectangular-head screw or bolt 21 (Fig. 4), the manner of associating the bracket with the screw, for bracket-mounting, being particularly referred to hereinafter.

The opposite bracket end 17 which, as before noted, projects oppositely to the end 16, relative to the plane of the body 15, is substantially identical in form and structure, with the latter end. It includes an intermediate portion 22 directed forwardly of the body at an obtuse angle thereto, and a rearwardly directed end portion 23 normal to the portion 22. A rectangular aperture or slot 24, similar to that in the portion 18 of end 16 and serving the same purpose, is provided in the portion 22 of end 17.

The relative arrangement of the two end structures or L-shaped terminals, in the finished form of the bracket, is such that the intermediate portions 18 and 22 are parallel, while the same applies to the end portions 19 and 23. Thus the bracket is symmetrically formed with respect to its preferably rectilinear body portion and is thus rendered readily reversible, end for end, without altering its intended dual function as a hanger type support for a lower shelf, and concurrently or conjointly as a support for the inner or wall-engaging end of an upper shelf. Moreover, the bracket is adapted through the end slots 20 and 24, for wall-mounting at either end, whichever one thereof engages the wall in a given shelf-assembly.

Mounting of the bracket to the wall 10 is attained in the following preferred manner: The bracket securing element 21 provided with a substantially rectangular head 25, being suitably located on and threaded into the wall, is arranged so that the major dimension of the head is horizontal (Fig. 4). The bracket is then held horizontally, with one end adjacent the head 25 in a position such that the slot (20 or 24) registers

therewith, whereupon the slotted end may be brought over and engaged with the element 21 by projection of the head 25 through the slot until the slot-containing bracket portion (18 or 22) is disposed between the wall and the head 25. After the last noted step, the bracket may be rotated about the element 21 as a pivot, into a vertical or shelf-supporting position. The bracket slot now having its major dimension at a right angle to the corresponding dimension of the head 25, the bracket will be thus effectively retained by the element 21, in its mounted position on the wall 10. The end portion (18 or 22) of the bracket provides as will now appear, a wall-bearing surface therefor, in the wall-mounted position of the bracket (Fig. 1). Removal of the bracket from its wall mounting, may be readily effected, merely by reversing the mounting procedure, as above described.

Referring to Figs. 1 and 2, a plurality or set of brackets 14 supporting the lowermost shelf 11 of the shelf-bank, are shown in one assembly position thereof, each with its end 16 hooked over the outer edge 30 of the shelf 11, such that the shelf edge rests upon the inner surface of the bracket end portion 19 and abuts the bracket portion 18. It is to be noted here and as shown in the drawing, that since the shelf 11 is the bottom or lowermost one in the bank, the inner or wall-abutting edge 31 thereof, may be supported by any suitable means, as the angle pieces 32.

The upper end 17 of each bracket 14 serving to support the edge 30 of shelf 11, is secured to the wall 10 in the manner hereinabove described, the end portion 23 thereof projecting horizontally outwardly from the wall. It is parenthetically noted that the term "wall" is utilized herein in a broad sense, in that it may consist of a separate vertical supporting strip of any suitable material, as well as a partition or building wall element of the usual forms. The term as thus utilized, may be defined as a vertical, ancillary structure along which the shelving is arranged, and by which it is supported through the hangers or brackets. The shelf 12 next above shelf 11, has its inner edge 33 seated upon the bracket end portion 23 which effectively provides for the support thereof. The outer edge 34 of shelf 12 is supported or suspended by another set of the brackets 14, these brackets however, for purposes of illustration, being reversed end for end and disposed in the same relative assembly positions occupied by the first set of brackets therebelow. As appears then, the end 17 of each is hooked over the outer edge 34 of the shelf, the shelf edge resting upon the inner surface of the bracket end portion 23 and abutting the portion 22. The opposite end 16 of each bracket is secured to the wall 10, as by the element 21 in the manner before described for the lower set of brackets, the end portion 19 of each now projecting horizontally from the wall 10 for support of the inner edge 35 of the top shelf 13 in the bank. The outer edge 36 of shelf 13 is suspended by a third set of the brackets 14, arranged similarly to either the first mentioned set of brackets or the second set.

It will be observed now, that with respect to the shelves 12 and 13 above the bottom shelf 11, these are supported or hung on wall 10 by the three sets of hanger brackets 14, which in cooperation with the wall 10, thus provide the sole supporting means therefor. The bottom or low-
ermost shelf 11 is the only one requiring sup-

porting means other than the brackets 14, for its inner edge 31. In the support of a single shelf, by brackets 14, the arrangement may be substantially similar to that described for the bottom shelf 11 of the bank illustrated, as will now appear. Moreover, it now becomes evident that by employing bracket elements of equal length, a uniform spacing of the shelves may be readily attained. Obviously, where it is desired to provide an unequal spacing of certain or all of the shelves in a given shelf-bank, such may be attained through the employment of bracket sets of unequal length in the respective superposed banks.

Figs. 5 and 6 illustrate a modification in the support of a shelf by the brackets 14. As there shown, and preferably utilized on the larger or more heavily loaded shelving, a channel-shaped member 31, preferably of metallic material, may be employed to strengthen the shelf transversely at the zones of its support by the brackets. The member 31 constitutes essentially, a bridge-piece between the upper end portion (19 or 23) of one bracket 14 and the lower end portion (23 or 18) of an adjacent bracket (Fig. 5), the ends of the member seating on these bracket portions and providing a continuous lateral bearing for the shelf. The channel members or other selected form of transverse bridge or brace, are preferably beveled off at their opposite ends as shown at 38, and are preferably secured to the under surface of the shelving as by screws 40, extending through apertures 41. The transverse reinforcing elements are thus, because of their beveled ends, kept out of substantial abutment with the wall or other vertical support, and by reason of screws 40, are removable with the shelving, from the hangers or brackets.

Fig. 7 illustrates the manner in which a plurality of the brackets may be grouped or nested, for shipping or storage purposes and the like. Disposition of them in relatively small or restricted spaces, is thus facilitated.

It will have appeared from the description of hanger or bracket structure and assembled shelving, that, in distinction from the prevailing types of shelf mounting elements, the tendency in the present design is for the weight of the shelf board, whether or not augmented by loading on the shelving, to draw in the lower end of the hanger or bracket element, i. e., to tend not only to pull the bracket closer in toward the shelving, but to tend to cause the shelving and bracket assembly closely to hug the wall or other vertical support on which the assembly is mounted.

It will further have appeared that, due to the relatively small area and linear extent of the legs of the right angle terminal portions of the hangers, each type of hanger of given dimensions, serves to accommodate a substantial range of different widths of shelving; for example, on a bracket or hanger in which the body portion is of 10½" length, the hanger may be utilized easily to accommodate shelving of widths varying between 10" and 12½". It is further to be noted that the right angle terminal portions or the L-shaped ends of the hanger, aid materially in causing the hanger to seat itself on the edge of the board or other shelving element, and tend also to effect a self-seating engagement between the hanger and the wall.

It will have further appeared that the substantially symmetrical construction of the hanger about the longitudinal axis of its body por-

tion, has a distinct advantage in assembly and erection in that it eliminates niceties of selection between ends of the hangers, and obviates the necessity for any distinction in mounting, between the upper and lower hanger or bracket ends.

It will further have appeared that the structure described fully attains each of the objectives hereinabove specifically stated, as well as others implied from the detailed description of a preferred embodiment.

While the foregoing description relates only to a preferred embodiment of the invention, as illustrated by the drawing, alterations and modifications may be made in the structure thereof, without departing from the scope and spirit of the invention as defined by the appended claims.

I claim:

1. A bracket of the type described, adapted for the support of a shelf on a wall or the like, the bracket being comprised of a one-piece metallic strip member terminating at its ends in reversely bent elements of like form, projecting laterally but oppositely, relative to the strip member, thereby adapting either end of the bracket member for supporting engagement with the overhanging edge of a wall-shelf, in a position such that the opposite end engages the wall, for securing of the bracket thereto.
2. A bracket of the type described, adapted for the support of a pair of adjacent, vertically spaced shelves on a wall or the like, the bracket being comprised of a one-piece metallic strip member terminating at its ends in reversely bent elements of like form, projecting laterally but oppositely, relative to the strip member, thereby adapting either end of the bracket member for supporting engagement with the overhanging edge of one of said shelves, in a position such that the opposite end of the member engages the inner or wall-abutting edge of the other shelf, for the support thereof.
3. A bracket of the type described, adapted for the support of a pair of adjacent, vertically spaced shelves on a wall or the like, the bracket being comprised of a one-piece metallic strip member terminating at its ends in reversely bent elements of like form, projecting laterally but oppositely, relative to the strip member, thereby adapting either end of the bracket member for supporting engagement with the overhanging edge of one of said shelves, in a position such that the opposite end of the member engages the inner or wall-abutting edge of the other shelf, for the support thereof, and engages also, the wall on which the shelves are arranged, for the support of the bracket thereon.
4. A suspension type shelf hanger or bracket, formed of a single metal strip and shaped to provide a rectilinear body portion of substantial length, and an L-shaped terminal element at each end of the body portion, said terminal elements extending laterally and oppositely, relative to the body portion, and the corresponding arm portions of the L-shaped elements being substantially parallel, whereby the bracket may be reversed, end-for-end, in the application thereof to the support of shelving.
5. A suspension type shelf hanger or bracket, formed of a single metal strip and shaped to provide a rectilinear body of substantial length, terminating at one end in an L-shaped element projected laterally of the body, and at its opposite end in a like L-shaped element projected laterally of the body and oppositely to the first said

element, said elements being of relatively short extent in relation to the length of the body and having the corresponding arm portions thereof arranged so as to be substantially parallel, and said elements each being apertured for selectively receiving means serving to secure the bracket to a wall or other support.

6. A suspension type shelf hanger or bracket, formed of a single metal strip and shaped to provide a rectilinear body of substantial length, terminating at one end in an L-shaped element projected laterally from one side of the body, and at its opposite end in a like L-shaped element projected laterally from the opposite side of the body, said elements being of relatively short extent as compared to the length of the body, and further, being relatively reversed in position such that the corresponding arm portions thereof are in substantial parallelism, whereby the bracket may be reversed, end-for-end, in the application thereof to the support of shelving, each of said elements being apertured for selectively receiving means serving to secure the bracket to a wall or other support.

7. A reversible wall-shelf bracket of the character described, comprising a one-piece strip member formed to provide at the ends thereof, substantially identical elements each adapted for supported engagement with a wall and for supporting engagement with a shelf.

8. A reversible bracket of the character described, comprising a one-piece strip member formed to provide substantially identical, angulate terminal elements at the ends thereof, the corresponding portions of said terminal elements being substantially parallel.

9. A reversible wall-shelf bracket of the character described, comprising a one-piece strip member formed to provide substantially identical, relatively reversed terminal elements at the ends thereof, the terminal elements being arranged on the strip member such that in either position of the bracket, one of said terminal elements serves to support one edge of one shelf and the other element the opposite edge of another shelf.

10 10. A reversible wall-shelf bracket of the character described, comprising a one-piece rectilinear strip member formed to provide substantially identical angulate terminal elements at the ends thereof, said elements being relatively reversed and arranged such that in either operative position of the bracket, one thereof is in supported engagement with a wall and in supporting engagement with one edge of a shelf, while the opposite angulate terminal element is thereby positioned for the support within the angulate terminal, of the opposite edge of another shelf.
